Primary Examiner — Mary Ann Calabrese*(74) Attorney, Agent, or Firm* — Boyle Fredrickson, S.C.(57) **CLAIM**

The ornamental design of a high chair with tray, as shown and described.

DESCRIPTION

FIG. 1 is a perspective view of a high chair with tray in accordance with the present invention;

FIG. 2 is a rear elevational view of the high chair with tray of FIG. 1;

FIG. 3 is a bottom view of the high chair with tray of FIG. 1;

FIG. 4 is a side elevational view of a first side of the high chair with tray of FIG. 1;

FIG. 5 is a side elevational view of a second side of the high chair with tray of FIG. 1;

FIG. 6 is a top view of the high chair with tray of FIG. 1; and,

FIG. 7 is a front elevational view of the high chair with tray of FIG. 1.

The broken lines in the drawings depict portions of the high chair with tray that form no part of the claim.
